Attorney

UNITED STATES PATENT OFFICE.

ALFRED G. F. KUROWSKI, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed October 27, 1923. Serial No. 671,066.

This invention relates to stencil card-holders for typewriting machines, and especially to a celluloid or other flexible backing sheet placed in the card-holder frame.

5 An object of the invention is to provide improved means for fastening the backing sheet to prevent bulging and bending.

A further feature of the invention is the manner of connecting the lower edge of the 10 backing sheet to the bottom of the card-holder frame, the sheet extending thence upwardly around the platen. This secures clear type-impressions.

One or more tabs of novel design on the 15 backing sheet engage slots in the bottom of the card-holder frame. On the frame holes are provided through which a pencil point may be inserted, to guide the tabs into the slots when assembling the backing.

20 Another novel feature is the permanent shaping of the celluloid backing sheet so that it will fit the contour of the platen at the printing line, in every position of the card-holder, thereby providing a satisfactory 25 supporting surface for the stencil card, so that clear-cut impressions are produced.

The principal object of this invention is to provide interlocking portions of the card-holder and the backing sheet or card that 30 by the act of inserting the card into the holder will cause such portions to engage and lock the card in position for writing; and which means, furthermore, may be integral with the card and with the bottom support 35 port on the holder for the card, respectively.

Other features and advantages will hereinafter appear.

In the accompanying drawings,

40 Figure 1 is a view, in front elevation, of a portion of a card-holder frame with the backing sheet shown attached thereto, and the stencil-card positioned thereon.

Figure 2 is a top plan view, partly in section, of a card-holder frame, showing 45 slots for attaching the backing sheet.

Figure 3 is a fragmentary bottom view of the device shown in Figure 2.

Figure 4 is an end elevation of the backing sheet, showing its permanent shaping.

50 Figure 5 is an end elevation of a portion of a typewriter, partly in section, with the invention attached thereto.

In the accompanying drawings a revolvable platen 10 carries a card-holder 11, and 55 types 12 strike against the front of the

platen. Card-holder 11 may be suspended from behind, over the platen 10, on a line-spacing mechanism, a portion of which is shown at 13. A complete card-holder mechanism is fully disclosed in my co-pending application No. 666,907, filed October 6, 1923. Card-holder 11 comprises upstanding frame members 14 and a lower cross-bar 15 in the form of a trough having a front, upstanding, flaring side 16, a bottom 17 and a rear, flaring side 18. A stencil-card 19 comprising a rectangular cardboard frame 20, to the rear of which is pasted a stencil-sheet 21, may be placed with its lower edge in the trough of cross-bar 15, with its side margins 70 within the card-holder sides 14 to position the stencil-sheet 21 to receive type-impressions, as shown in Figures 1 and 5. A backing sheet or backing piece 22, which may be made of celluloid, or other material having suitable properties, is fastened close to the back edge of the bottom 17 of the cross-reach 15, and forms a pocket in which the stencil-card 19 is easily insertible. Backing sheet 22 also supports the stencil-card 19 to 75 prevent bulging and bending thereof during the typing operation, so that clear-cut type-impressions may be produced.

The bulging and bending of the stencil-card 19 is further avoided during the typing operation by fastening the backing sheet 22 at its lower edge only to the back edge of the bottom 17. This allows the backing sheet 22 to be free to extend upwardly, around the platen 10 at the printing line, in each position of the card-holder. The sheet 22 may be given a permanently curved shape, as shown in Figure 4, so that it will better fit the contour of the platen 10 at the printing line, and thereby always present a satisfactory supporting surface against which the types 12 can strike. For attaching the sheet 22 to the card-holder 11, a shaped-tab 23 may preferably be provided at each end of the lower edge of sheet 22. Radially-shaped slots 24 in the trough in bottom 17 are provided and spaced to receive tabs 23. Each tab 23 is formed of a lip portion 25 and a projection 26. When tabs 23 are first introduced into slots 24, they are compelled to curve slightly, due to the radial shape of slots 24, see Figure 2, until the lower edge of the backing sheet 22 reaches the bottom 17, at which time the projection 26 will straighten out and will 100 105 110

permanently hold the sheet 22 in place. The sheet 22 can be removed by tearing tabs 23 out of the card-holder 11. The lips 25 have blunt-pointed leading edges to guide 5 the tabs 23 into the slots 24.

To facilitate the insertion of tabs 23 in slots 24, holes 27 are provided in line with the slots 24 on the front, upstanding, flanged side 16, through which a lead-pencil point 10 may be inserted to push back the tabs 23, so as to bring them in alignment with the slots 24. The leading edges of lips 25 will then readily enter and guide tabs 23 into slots 24. In order to prevent the tabs 23 from interfering, or being interfered with, 15 by any part of the carriage, angle projecting pieces 28 mounted on the downwardly facing side of the bottom 17 and extending around slots 24 may be provided to guard 20 the tabs 23, see Figures 1 and 5.

It will be understood that the bottom plate 17 of the holder has a slot at 24, with an extension 4 that projects laterally, being shown as curved. It will be further understood 25 that the tab 25 projecting with the lower edge at one or more places has an extension 26 deflected laterally, or to the left; and the lower wall 6 of the tab extends downwardly 30 away from the free end of the portion 25 to the middle portion; while the other portion of the tab may have the lower edge 7 extending upwardly from the middle portion. This forms a somewhat angular lower 35 edge that will assist in directing the tab to the slot 24.

When the card is moved downwardly and enters the slot 24 at the main portion, the inclined edge 26 of the tab will engage the deflected portion 4 of the slot, that will 40 have a kind of double cam action serving to deflect the tab free extension in the direction of the deflected slot, and the engagement will be progressive from the lower edge of the extension to the free end, and from the connection of the deflected slot-portion to its other end. When the tab penetrates the slot, 45 it will pass beneath the wall 17 and will naturally tend to flatten at the bent free projection, which will bring it beneath the 50 margin of the slot-extension and prevent withdrawal of the tab. It will be further understood that this locking means comprises simply an integral portion of the card, that 55 co-operates with an integral portion of the bottom plate 17, being merely a slot therein.

Variations may be resorted to within the scope of the invention, and portions of the improvements may be used without others.

Having thus described my invention, I 60 claim:

1. The combination, in a typewriting machine having a revoluble platen, of a stencil-card-holding frame arranged to reciprocate in front of the platen, said frame having side 65 arms connected by a bottom cross-piece, and

means for positively securing a formed backing-sheet to said cross-piece, said backing-sheet serving as a rear support for the stencil-card, which backing-sheet together with the card-holding frame forms a curved 70 pocket for the card.

2. The combination, in a typewriting machine having a revoluble platen, of a stencil-card-holding frame arranged to reciprocate 75 in front of the platen, said frame having side arms connected by a bottom cross-piece, and means for positively securing a formed backing-sheet to said cross-piece, including hooks 80 projecting downwardly from the bottom edge of said backing-sheet, said hooks being designed to hold the backing-sheet in its effective position by engaging locking slots in the card-holding frame, said backing-sheet serving as a rear support for the stencil-card, the backing-sheet together with the 85 card-holding frame forming a curved pocket for the card.

3. In a typewriting machine, a platen, a card-holder mounted adjacent to the platen, interlocking means for fastening a backing 90 sheet by its lower edge to the card-holder, said means comprising a tab at the lower edge of said sheet, and a slot for engaging the tab in the lower cross-reach of the card-holder. 95

4. The combination, in a typewriting machine having a revoluble platen, of a stencil-card-holding frame arranged to reciprocate tangentially in front of said platen, said card-holding frame having side-supporting 100 arms and a bottom cross-bar forming an integral part of said supporting arms, said cross-bar having locking slots designed to engage with hooks projecting from the bottom edge of a celluloid backing-card in a 105 manner to effectively hold the card in its operating position, said cross-bar having also holes adjacent said locking slots, through which holes a pointed tool may be inserted to guide the hooks into engagement with the 110 slots in the card-holding frame.

5. In a typewriting machine, a platen, a card-holder mounted adjacent to the platen, and interlocking means for fastening a backing sheet by its lower edge to the card-holder, said means comprising tabs extending from the lower edge of said sheet, and slots for engaging the tabs in the lower cross-reach of the card-holder, said lower cross-reach having holes adjacent said tabs, 115 through which holes a pointed tool may be inserted to force said tabs into engagement with the slots in the cross-reach. 120

6. In a typewriting machine, a platen, a card-holder mounted adjacent to the platen, interlocking means for fastening a backing sheet by its lower edge to the card-holder, said means comprising a blunt-pointed tab 125 extending from the lower edge of said sheet, a slot in the bottom of the card-holder, and 130

- a hole in the front upstanding side of the cross-reach of the card-holder through which the tab may be directed to enter the slot, said tab having a projection formed thereon, which, on being inserted in the slot, locks the backing sheet to the card-holder.
7. In a typewriting machine, a platen, a card-holder mounted adjacent to the platen, interlocking means for fastening a backing sheet by its lower edge to the card-holder, said means comprising a tab extending from the lower edge of said sheet, and a slot for engaging the tab in the lower cross-reach of the card-holder, and means to guard the tab against injury.
8. In a typewriting machine, a platen, a card-holder mounted adjacent to the platen, interlocking means for fastening a backing sheet by its lower edge to the card-holder, said means comprising a tab extending from the lower edge of said sheet, and a slot in the bottom of the card-holder, a hole in the front upstanding side of the cross-reach of the card-holder through which the tab may be directed to enter the slot said tab having a projection formed thereon, which, on being inserted in the slot, locks the backing sheet to the card-holder, and a guard on the bottom side of said bottom of the card-holder around the slot to protect the tab from interference.
9. The combination, in a typewriting machine, of a revoluble platen, and a work-supporting member mounted adjacent to the platen, said member having a permanently curved shape for supporting a work-piece contacting with the platen at the printing line to enable clear-cut type-impressions to be made on the work-piece, said supporting member co-operating with a celluloid sheet attached thereto to hold the work-piece therebetween.
10. In a typewriting machine, a revoluble platen, a card-holder mounted adjacent to the platen, and a flexible backing sheet, having a permanently curved shape, for supporting a work-piece tangent to the platen at the printing line to enable clear-cut type-impressions to be made on the work-piece in any position of the card-holder.
11. In a typewriting machine, a revoluble platen, a card-holder mounted adjacent to the platen, a backing sheet for said holder, and fastening means between the lower portion of said sheet and the card-holder which
- allows the upper portion of the sheet to rest against the platen at the printing line in any position of the card-holder, said sheet having a permanently curved shape for supporting a work-piece tangent to the platen at the printing line to enable clear-cut type-impressions to be made thereon in any position of the card-holder.
12. The combination, in a typewriting machine, of a revoluble platen, a card-holder mounted adjacent to the platen, a backing-sheet for said holder, and means for fastening said sheet to the card-holder in a manner to present the sheet to the platen at the printing line, said sheet being permanently curved to contact with the platen in a manner to enable clear-cut type-impressions to be made on the sheet in any position of the card-holder.
13. A card-holder having at the bottom a longitudinally slotted wall with a deflected extension, and a card with a tab at the lower part having a portion projecting longitudinally with its lower edge inclined downwardly away from the free end, whereby the tab as moved downward will engage progressively at said inclined edge-portion along the wall of said slot-extension to bend said tab-projection laterally, until the tab penetrates the slot and thereupon flattens to normal position, to project beneath the slotted wall-margin and prevent withdrawal from the slot.
14. A card-holder having at the bottom a longitudinally slotted wall with a deflected extension, and a card with a tab at the lower part having a portion projecting longitudinally with its lower edge inclined downwardly away from the free end, and thence inclined upwardly to the other end of the tab, whereby the tab as moved downward will engage progressively at said inclined edge-portion along the wall of said slot-extension to bend said tab-projection laterally until the tab penetrates the slot and thereupon flattens to normal position, to project beneath the slotted wall-margin and prevent withdrawal from the slot.
15. A card-holder having locking slots, and a card having a locking hook forming an integral part thereof, said hooks being arranged to latch the card in its normal position when the same is lowered into the holder.

ALFRED G. F. KUROWSKI.
